PHOTOISOMERIC PREPARATION OF TRANS BIS ORGANOSULFONYL ETHYLENES

James D. Johnston, Baton Rouge, La., assignor to Pittsburgh Chemical Company, Pittsburgh, Pa., a corporation of Pennsylvania

No Drawing. Filed July 15, 1960, Ser. No. 42,971

7 Claims. (Cl. 204—158)

This invention relates to the conversion of cis bis organosulfonyl ethylenes and haloethylenes to the corresponding trans bis organosulfonyl ethylenes and haloethylenes.

Bis organosulfonyl ethylenes and haloethylenes have been found to be good fungicides. Johnston Belgian Patent 543,377, June 6, 1956, Raasch United States Patent 2,893,911 and Riden Belgian Patent 567,981, June 14, 1958.

The trans isomer has been found in many cases to be superior to the cis isomer. Unfortunately, the normal procedures for preparing the bis organosulfonyl ethylenes and haloethylenes either prepare the cis isomer or a mixture of cis and trans isomers containing a large proportion of the cis isomer.

Accordingly, it is an object of the present invention to convert cis bis organosulfonyl ethylenes and haloethylenes to the corresponding trans compounds.

Another object is to convert cis bis alkyl sulfonyl ethylenes to the corresponding trans compounds.

A more specific object is to convert cis bis n-propyl sulfonyl ethylene to trans n-propyl sulfonyl ethylene.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

It has now been found that these objects can be attained by treating a cis bis organosulfonyl ethylene or haloethylene with bromine, preferably in the presence of ultraviolet light.

As the starting cis organosulfonyl ethylenes and haloethylenes there can be employed compounds having the formula

where Q_1 and Q_2 are selected from the group consisting of alkyl having 1 to 18 carbon atoms, phenyl, lower alkyl phenyl, benzyl, chlorophenyl, bromophenyl, nitrophenyl and naphthyl and X_1 and X_2 are selected from the group consisting of hydrogen and halogen. Preferably Q_1 and Q_2 are both alkyl groups of 2 to 5 carbon atoms and preferably both X_1 and X_2 are hydrogen.

As typical examples of cis organosulfonyl ethylenes and haloethylenes which can be converted to the corresponding trans isomers there can be used

1,2-bis(methylsulfonyl) ethylene;
1,2-bis (ethylsulfonyl) ethylene;
1,2-bis (n-propylsulfonyl) ethylene;
1,2-bis (isopropylsulfonyl) ethylene;
1,2-bis (n-butylsulfonyl) ethylene;
1,2-bis (isobutylsulfonyl) ethylene;
1,2-bis (t-butylsulfonyl) ethylene;
1,2-bis (amylsulfonyl) ethylene;
1,2-bis (sec. butylsulfonyl) ethylene;
1,2-bis (hexylsulfonyl) ethylene;
1,2-bis (heptylsulfonyl) ethylene;

2

- 1,2-bis (octylsulfonyl) ethylene;
1,2-bis (nonylsulfonyl) ethylene;
1,2-bis (decylsulfonyl) ethylene;
1,2-bis (dodecylsulfonyl) ethylene;
1,2-bis (octadecylsulfonyl) ethylene;
1,2-bis (benzylsulfonyl) ethylene;
1,2-bis (phenylsulfonyl) ethylene;
1,2-bis (o-tolylsulfonyl) ethylene;
1,2-bis (p-tolylsulfonyl) ethylene;
1,2-bis (m-tolylsulfonyl) ethylene;
1,2-bis (2-naphthylsulfonyl) ethylene;
1,2-bis (o-nitrophenylsulfonyl) ethylene;
1,2-bis (p-nitrophenylsulfonyl) ethylene;
1,2-bis (m-nitrosulfonyl) ethylene;
1,2-bis (o-chlorophenylsulfonyl) ethylene;
1,2-bis (p-chlorophenylsulfonyl) ethylene;
1,2-bis (m-chlorophenylsulfonyl) ethylene;
1,2-bis (o-bromophenylsulfonyl) ethylene;
1,2-bis (ethylsulfonyl)-1,2-dichloroethylene;
1,2-bis (methylsulfonyl)-1,2-dichloroethylene;
1,2-bis (n-propylsulfonyl)-1,2-dibromoethylene;
1,2-bis (n-propylsulfonyl)-1,2-difluoroethylene;
1,2-bis (n-propylsulfonyl)-1,2-diiodoethylene;
1,2-bis (isopropylsulfonyl)-1,2-dichloroethylene;
1,2-bis (n-butylsulfonyl)-1,2-dichloroethylene;
1,2-bis (ethylsulfonyl)-1-chloro-2-fluoroethylene;
1-(methylsulfonyl)-2-(ethylsulfonyl)-1,2-dichloroethylene;
1-(n-propylsulfonyl)-2-(n-butylsulfonyl) ethylene;
1,2-bis (dodecylsulfonyl)-1,2-dichloroethylene;
1,2-bis (methylsulfonyl)-1-chloroethylene;
1,2-bis (ethylsulfonyl)-1-chloroethylene;
1,2-bis (n-propylsulfonyl)-1-chloroethylene;
1,2-bis (n-propylsulfonyl)-1-bromoethylene;
1,2-bis (n-propylsulfonyl)-1-fluoroethylene;
1,2-bis (isopropylsulfonyl)-1-chloroethylene;
1,2-bis (n-butylsulfonyl)-1-chloroethylene;
1,2-bis (isobutylsulfonyl)-1-chloroethylene;
1,2-bis (sec. butylsulfonyl)-1-chloroethylene;
1,2-bis (tert. butylsulfonyl)-1-chloroethylene;
1-methylsulfonyl-2-butylsulfonyl-1-chloroethylene;
1-propylsulfonyl-2-butylsulfonyl ethylene;
1,2-bis (octylsulfonyl)-1-chloroethylene;
and 1,2-bis (octadecylsulfonyl)-1-chloroethylene.

Since most of the cis organosulfonyl compounds set forth above are solids, it is desirable to carry out the isomerization in the presence of a solvent. The preferred solvents are hydrocarbons and halohydrocarbons such as benzene, toluene, xylene, ethylene dichloride, 1,1,2-trichlorethane, carbon tetrachloride, carbon tetrabromide, trichloroethylene, methylene chloride, perchloroethylene and chloroform.

Only a few drops of bromine need be added, although considerably more bromine can be employed but this is not preferred for economic reasons.

The ultraviolet irradiation can be carried out with a conventional sunlamp or any other source of ultraviolet light. Ultraviolet light irradiation of the cis isomer in the absence of bromine did not cause isomerization.

The isomerization reaction goes satisfactorily at room temperature but either elevated or reduced temperatures can be employed.

In the specification and claims, all parts and percentages are by weight unless otherwise indicated.

Example 1

20 grams of bis (p-tolylsulfonyl) ethylene (35% cis 70 isomer and 65% trans isomer) and 100 ml. of chloroform were placed in a flask and two drops of a concentrated bromine solution in carbon tetrachloride were

added. The orange color persisted even on warming. The flask was irradiated with a sunlamp and the orange color was rapidly dissipated with the formation of a precipitate. More bromine solution was added slowly until the orange color was not discharged on standing. The product was collected by filtration, washed with chloroform until white and dried. There were collected 12.8 grams of trans 1,2-bis (p-tolylsulfonyl) ethylene, melting point 225-227° C. There were recovered by concentration of the mother liquor an additional 6.2 grams of the trans compound.

Example 2

25.5 grams of the pure cis 1,2-bis (n-propylsulfonyl) ethylene was dissolved in 150 ml. of carbon tetrachloride and a few drops of bromine added. The mixture was then irradiated with an ultraviolet light lamp (sunlamp). A copious precipitate formed as soon as the light source was turned on. After fifteen minutes, this precipitate was removed from the filtrate by filtration and air dried free of carbon tetrachloride. The precipitate weighed 25 grams. The melting point of the precipitate was 155-156° C. which is the melting point of pure trans 1,2-bis (propylsulfonyl) ethylene. (The cis isomer melts at 42-44° C.)

The same isomerization was observed when the carbon tetrachloride in Example 2 was replaced by benzene, ethylene dichloride, 1,1,2-trichlorethane, trichloroethylene, methylene chloride and perchloroethylene.

The results obtained are surprising since other methods which have been employed for converting cis isomers to trans isomers are ineffective. Among such procedures which do not work with the organosulfonyl ethylenes are heating the cis isomer to 150° C. for 28 hours.

What is claimed is:

5

10

15

20

25

30

35

1. The method of converting the cis isomer of a compound having the formula

wherein Q_1 and Q_2 are selected from the group consisting of alkyl, aryl, haloaryl and nitroaryl and X_1 and X_2 are selected from the group consisting of hydrogen and halogen to the trans isomer comprising treating said cis isomer with bromine in the presence of ultraviolet light.

2. A method according to claim 1 wherein the cis compound is dissolved in a solvent.

3. A method according to claim 2 wherein X_1 and X_2 are both hydrogen.

4. The method of converting the cis isomer of a bis-alkylsulfonyl ethylene to the trans isomer comprising treating said cis isomer with bromine in the presence of ultraviolet light.

5. A method according to claim 4 wherein the cis compound is dissolved in a solvent.

6. A method according to claim 5 wherein the alkyl groups have 2 to 5 carbon atoms each.

7. The method of converting cis bis(n-propylsulfonyl) ethylene to trans bis (n-propylsulfonyl) ethylene comprising treating said cis isomer while dissolved in a solvent with bromine in the presence of ultraviolet light.
